DESIGN FOR AN APPLIQUÉ EMBLEM FOR ARTICLES OF APPAREL

Charles Emmey, New York, N. Y.

Application January 14, 1936, Serial No. 60,571

Term of patent 3½ years

To all whom it may concern:

Be it known that I, Charles Emmey, a citizen of the United States and resident of New York city, in the county and State of New York, have invented a new, original, and ornamental Design for an Appliquéd Emblem for Articles of Apparel, of which the following is a specification, reference being had to the accompanying drawing, forming part thereof.

The figure is a plan view of an appliquéd em-

blem for articles of apparel showing my new design.

The appliquéd emblem for articles of apparel shown in the drawing is of no appreciable thickness.

I claim:

The ornamental design for an appliquéd emblem for articles of apparel substantially as shown and described.

CHARLES EMMEY.
